AUTOMATIC TAG THREADING MACHINE

Roy G. Travis, Wilmette, Ill., assignor to International Tag & Salesbook Company, Chicago, Ill., a corporation of New Jersey

Application May 3, 1935, Serial No. 19,667

33 Claims. (Cl. 93—91)

The present invention relates to automatic tag threading machines.

Heretofore machines have been provided for automatically threading a length of string through an opening in a tag for securing the same thereto. These machines consist of a plurality of complicated mechanisms all of which must be very accurately adjusted in order to secure the desired results, and have been very difficult to maintain in operating condition due to the large number of parts subjected to severe wear, and because of the plurality of complicated movements involved the parts have become easily out of adjustment, and in many instances broken, thereby necessitating the complete shut-down of the machine for replacement of these broken or worn parts.

The present invention accordingly contemplates an automatic tag threading machine which is radically different in its construction from machines which have been used heretofore, the design being based primarily on simplicity of operation wherein a minimum of movable parts has been provided to effect the necessary steps in the threading operation in order to eliminate complications in the operation of the machine and the necessity for continual replacement, adjustment or repair.

The present invention comprehends the idea of providing a novel loop forming and threader mechanism operable substantially in a vertical plane and to which a thread or string is fed in substantially a horizontal plane.

The present invention also includes as an object the idea of providing a novel string control means which is associated with the loop forming and threader means for controlling the thread which is fed to the threader means in a substantially horizontal plane.

Another object within the purview of the present invention is to provide a novel string feeding and measuring means which is constructed for the purpose of feeding the string to the loop forming and threader means and for severing the desired length of string for each separate threading operation.

More particularly, the present invention comprehends the idea of operating this string feeding and measuring means in substantially a horizontal plane, and further includes means whereby the same may be readily adjusted to measure varying lengths of string, as desired.

Still another object of the present invention is to provide a complete automatic tag threading machine having various parts and elements co-

operating with the parts above enumerated whereby the complete threading operation may be readily and easily effected.

Other objects, features, capabilities and advantages are comprehended by the invention, as will later appear and as are inherently possessed thereby.

Referring to the drawings:

Figure 1 is a view in front elevation of a tag threading machine made in accordance with the present invention;

Figure 2 is a horizontal cross sectional view taken in the planes represented substantially by the line 2—2 of Figure 1 of the drawings;

Figure 3 is a fragmentary vertical cross sectional view taken substantially in the plane represented by line 3—3 of Figure 2 of the drawings;

Figure 4 is a fragmentary view in elevation of the string feeding means of Figure 1 of the drawings and the control means therefor;

Figure 5 is a detached plan view of a string control means, using the device shown in Figure 1 of the drawings;

Figure 6 is a view in side elevation of the string control means of Figure 5 of the drawings;

Figure 7 is a detached plan view of threader means for the device;

Figure 8 is a plan view of the loop threader means of the device;

Figures 9 to 12 inclusive are views showing the tag and various steps in the threading operation; and

Figure 13 is a fragmentary view of the tag showing the string as attached thereto.

Referring now more in detail to the drawings, an automatic tag threading machine made in accordance with the present invention is shown as comprising a base 2 having a top 4 supported thereon and above which various operations in the threading of string into the tags take place. Located at one end of the table or top 4 is a tag magazine 6 for holding a stack of tags 8, which tags are constructed as disclosed in Figures 9 to 13 inclusive of the drawings, and preferably comprise a sheet 10 of flexible fibrous material, such as cardboard or the like, which is formed with an opening 12 adjacent one end and centrally thereof, of which opening is reinforced as clearly shown in Figure 10 of the drawings by the annular members 14 and 16 secured to both sides of the sheet 10 adjacent the opening.

The present invention comprehends suitable mechanism for automatically securing a piece of string 18 to the tag 10, this securing being effected by the loop 20 on one side of the tag through 55

which, on the other side of the tag pass the free ends of string 18, this loop securing the string to the tag.

The machine for accomplishing this threading operation automatically includes a pulley 22 mounted upon the shaft 24 journaled in the base or frame 2, this pulley being rotated by means of a belt which is driven by any suitable source of power, such as an electric motor or the like. Fixed to the shaft 24 is a sprocket 26 and a gear 28, the sprocket 26 through the chain 30 operating sprockets 32 and 34, as will be hereinafter more fully disclosed, while pinion 28 meshes with and drives a gear 36 mounted upon a shaft 38 journaled in the frame or base 2 of the device.

This gear 36 is formed with a cam groove 40 in one face thereof within which is disposed a roller 42 secured to feeder arm 44, this feeder arm being pivoted at 46 to the frame or base 2 at one end and being pivotally connected at 48 to a feeder carriage 50, which carriage at its forward end has an upwardly projecting pin 47 which is adapted to project into the opening 12 of the lowermost tag 10 in the magazine 6 and move the same forwardly to the position shown in Figures 1 and 3 of the drawings whereby the opening 12 is disposed directly beneath the needle or threadder 52 of loop forming and threadder mechanism generally referred to as 54. It is understood, of course, that arm 44 oscillates intermittently to successively transfer the lowermost tag from the magazine 6 to the position as shown in Figures 1 and 3 to receive string which is attached thereto, as shown in Figure 13 of the drawings, by the mechanism to be hereinafter more fully disclosed.

Mounted in back of the gear 36 and upon the shaft 38 is a cam member 56 having a cam groove 58 formed in one face thereof and a cam groove 59 formed in the other face thereof. Operable within the cam groove 58 is a roller 60 secured to the lowermost end of lever 62 which is fulcrumed at 64 to the frame or base 2 and to the upper end of which, as at 70, (see Figure 8) is pivotally secured the spaced arms 66 and 68, these arms being normally pulled toward one another as by means of the coil spring 72. These arms 66 and 68 straddle a bracket 74 which has an enlarged head 76 which tends to spread these arms apart about their pivot points 70 as the arms move thereover due to the movement of lever 62 about its pivot 64. This movement of lever 62 of course is in accordance with the curvature of the cam groove 58. These arms terminate at their upper ends in the laterally disposed and curved points 78 adapted to engage the string forming the loop 20 and to spread the same apart, as will be more fully disclosed hereinafter.

Operable within the cam groove 60 is a roller 80 secured to the lower end of lever 82 which is fulcrumed about the shaft 84 secured to the frame or base 2 of the machine. The upper end of the lever 82 is provided with a transversely disposed shelf 86, upon which is mounted the threadder arms 88 and 90 by means of the pivot bolt 92. The lower ends of these arms 88 and 90 are connected together by means of a coil spring 94 which tends to maintain the upper ends of the arms in closed position and in contact with one another. The lower ends of the arms have the plates 96 attached thereto which normally are in abutting engagement but serve to spread the upper ends of the arms 88 and 90 apart upon their engagement with a wedge member 98 secured to the table or top 2, as at 100.

Also disposed within the cam groove 60 is a roller 102 connected to arm 104 which is pivoted as at 106 to the frame or base, a second arm 108 being operatively connected to the roller 102 whereby this arm is adapted to oscillate an arm 110 connected to the shaft 112 of the loop forming and threadder mechanism 54. This shaft is provided with the radially extending portion 114 which, together with a plate 116 removably secured thereto as by means of screws 118, provides a mounting for the curved needle or threadder 52, this needle or threadder being replaceable because of the removability of plate 116 and being provided with an open eye 120 formed with a shoulder at the upper end thereof.

The chain 30, as previously indicated, drives the sprocket 34 of string feeding mechanism generally referred to as 35, which is mounted upon the bracket 132 adjustably mounted upon the table 4 by means of bolts 133 in openings 135 thereof. This sprocket 34 is mounted upon a transversely disposed shaft 122 journaled in the bracket 132 and has a beveled pinion 124 mounted thereon adapted to drive a beveled gear 126 mounted upon the vertically disposed shaft 128 journaled in the bearing 130 provided in the bracket 132. This vertically disposed shaft 128 is formed with an enlarged head 134 disposed below the bearing 130 and abutting against the lower end thereof. This shaft 128 is rotated through shaft 122, pinion 124 and gear 126, and is provided with a transversely disposed bore 136 adapted to receive the cylindrical end 138 of the string feeding or measuring arm 140, this arm being adjustably secured in bore 136 by means of a set screw 142. The arm 140 is provided with an integral fixed jaw 144 to which is pivoted a movable jaw 146 as at 148, a cutting knife 150 being pivotally secured on the pivot 148 adjacent the movable jaw 146 and has its lower knife edge 152 disposed to cooperate with the edge 154 of the fixed jaw 144 to sever the string, as hereinafter to be more fully disclosed. The pivotal jaw 146 is normally maintained in closed relation with fixed jaw 144 by means of a coil spring 156 mounted upon a rod 158 and disposed between abutment 160 on the arm 140 and the upper end 162 of the movable jaw 146, the rod 158 being provided with a tapered end received within a recess in the upper end 162 of the movable jaw whereby the rod is loosely associated with the upper end 162 of the movable jaw to permit movement of said jaw, the rod being guided within the transverse opening 164 of the abutment 160.

Mounted upon the table 4 is a bracket 166 having the substantially vertical supports 168 and 170 and upon which are mounted rollers 172 and 174, respectively, substantially in the path of movement of the movable jaw 146 and the movable cutting element 150, respectively. At one point in the travel of the string feeding and measuring arm 140, the upper end 162 of the movable jaw 146 engages roller 172 whereby the jaw is moved away from the fixed jaw 144 about its pivot 148 to release the string carried thereby. The string, however, which has been carried along during the movement of the arm 140 is disposed in position to enter between jaws 144 and 146 when opened, and after the upper end 162 of movable jaw 146 passes over roller 172 and closes this string is grasped between jaws 144 and 146 whereby the string is again carried along, as will be later described. The roller 174 is in the path of the lower end of movable knife 150 and when 75

5 this knife engages with the roller, the same is moved toward the edge 154 of jaw 144 to sever the end of the forward section or length of string which has been previously released from between jaws 150 and 144, as will be later described more in detail, this movement of the knife 150 being limited by the pin 176 fixed to the upper end 162 of the movable jaw and operable within slot 178 in the upper end of the knife.

10 The string 180, as shown in Figure 1 of the drawings, is drawn from a suitable source by the string feeding and measuring arm 140 through opening 182 formed in the top or table 4 and through a tensioning device 184 and around the 15 hook shaped guide 186. The string, after being gripped between jaws 144 and 146, is drawn through the tensioning device 184 from the source and carried around pins 188 and 190 of the string control means, generally referred to as 192. This 20 string control means comprises a plate 194 fixed to the top 4 of the machine and the intermediate and top spring plates 196 and 198, respectively, these plates being provided with spaced arms forming a slot 200 to receive the thresher 52 and 25 mounting therefor whereby the same is operable within a plane normal thereto. The arms of plates 196 and 198 are loosely secured to the plate 194 by means of the bolts 202 and 204 and washers 206 and 208 are interposed between plates 30 194 and 196 and 198 to properly space these plates. The plate 196 at the end opposite the arms thereof is secured to plate 194 by rivet 210 and spaced therefrom by the washer 212. Intermediate the rivet 210 and bolts 202 and 204 35 are the bolts 214 and 216 passing through openings 218 in the lower plate 194 and being secured to the intermediate spring plate 196. Spring plate 196 is held in association with plate 194 by means of the coil springs 220 intermediate the heads 40 of the bolts 214 and 216 and the under side of plate 194. Plate 194 is formed at its other end with openings 222 and 224 into which project the pins 188 and 190, respectively, which are connected to the arms of plate 198 and pass downwardly through openings 226 in the arms of plate 196, plate 196 adjacent these openings being provided with the protuberances 228 normally held in engagement with the plate 194 by means of springs 220. Fixed to the arms of plate 194 are 45 pins 230 and 232 which project upwardly through openings 234 and 236 formed in the arms of plates 196 and 198, respectively. Pins 188 and 190 are normally disposed within the openings 222 and 224 under the action of spring plates 238 and 240, 50 which have an end engageable with the arms of the plate 198 adjacent the pins 230 and 232 and an end secured to the bolts 202 and 204 between the nuts 242 therefor and the upper surface of the arms of plate 198. Pins 188 and 190 are 55 moved upwardly out of the openings 222 and 224 of the plate 194 during certain operations of the machine by the inner end of plate 198 which has a protuberance 244 engaged by the protuberance 246 formed on the under surface of the enlarged head 134 of the shaft 128.

60 For the purposes of illustrating the operations of this machine, let us assume that the string measuring arm has passed the roller 174 and the knife member 150 has been operated to sever a portion of string preceding the portion of string 65 the end of which is secured between the fixed and movable jaws 144 and 146. The arm 140 is rotated in a counter-clockwise direction, as viewed in Figure 2 of the drawings, and with the end of 70 the string 180 between the jaws 144 and 146 75

thereof, continues to rotate from the roller 174 toward the thresher or needle 52 in a circular path. This movement continues to draw the string 180 from the source through tension device 184 around the guide 186 and a guide 248 located on the table 4 substantially opposite the rollers 172 and 174. During this movement, the tag 8 which has been previously threaded, is discharged from table 4 in the manner to be presently described, and the feeder carriage 50 has moved to present another tag with its opening 12 disposed directly below and in the path of movement of the thresher or needle 52. After the tag 8 has been moved to this position, the projection 41 of the feeder carriage 50 drops downwardly out of engagement with the opening 12 and is moved by arm 44 beneath the magazine 6 to engage the next tag which is to be moved into a position for threading. As the feeding arm 140 continues its counter-clockwise movement, the string 180 successively engages protuberances 228 passing between the same and the plate 194 to engage pins 188 and 190 substantially as shown in Figure 5. The arm then continues this counter-clockwise movement slightly beyond the position of the arm 25 as indicated in Figure 5, at which time protuberance 246 of the rotating head 134 engages the protuberance 244 of plate 198 to move pins 188 and 190 upwardly whereby the central part of the string passes around pins 230 and 232 and 30 into a position to be engaged by the shoulder of eye 120 of needle 52. The pins 188 and 190, after disengagement of protuberances 244 and 246, return to their normal projecting position within openings 234 and 236. The jaws continue to 35 move in a circular path into a position substantially opposite the roller 172. During this travel the needle or thresher 52 is moved downwardly in a circular path by the lever arm 108 and when the jaws are in the vicinity of rollers 172 and 174 40 engage the central portion of the string, as shown in Figure 9 of the drawings. Continued downward movement of needle 52 causes the central part of the string (which has been cut as will be described) to be threaded through opening 12 45 to form a loop on the under side of the tag 8. After this loop has been formed, the string forming the loop is engaged by the laterally projecting portion 78 of the arms 66 and 68 and spread apart, as shown in Figure 11 of the drawings, it 50 being understood that lever 62 has been operated to move arms 66 and 68 to a position to engage the loop and to engage wedge 76 to effect a spreading of the loop. These spreader arms 66 and 68 therefore form an enlarged loop on the under side 55 of the tag and tend to pull this loop away from the tag, as clearly indicated in Figure 11 of the drawings.

55 It is of course understood that previous to the complete formation of this loop on the under side 60 of the tag, the arm 140 has rotated whereby the roller 172 has engaged the upper end 162 of the movable jaw 146 to release the forward end of the string 180 which has been moved in a circular path, as above described. Immediately upon release of this end of the string, the string is again 65 grasped between the jaws 144 and 146 as the arm 140 passes beyond roller 172. The arm 140 proceeds in its counter-clockwise movement whereby the roller 174 immediately engages knife 150 to 70 move the same and to cut the forward end portion of the string which is to form the loop of Figure 11 of the drawings. It is after this cutting operation that the thresher 52 completes the loop through the opening 12 of the tag and the arms 66 75

and 68 engage the same to form an enlarged loop and to draw this loop away from the tag. During the formation of the loop, lever 82 has been moved as described, and as the loop is being enlarged the fingers 88 and 90 moved thereby pass through the loop and upon engagement of the plates 96 thereof with wedge member 98 are opened to embrace the free ends 250 and 252 of this cut section of string. The arms are closed upon disengagement of wedge 98 with plates 96 whereby these free ends 250 and 252 are disposed and held between the forward ends of arms 88 and 90. The movement of the lever 82 is such as to draw these free ends through the enlarged loop, as clearly shown in Figure 12 of the drawings, to secure this section or portion of string to the tag 8.

During the final step of drawing the free ends 250 and 252 through the loop, the arms 66 and 68 are again brought together under the action of spring 72 by movement over the wedge 76 to release their engagement with the loop whereby the tag 8 may be discharged after the free ends 250 and 252 have been drawn through the loop by the arms 88 and 90. During this final step in the operation, the arm 140 has continued to rotate in a counter-clockwise direction and to draw another section or portion of string around the pins 188 and 190, and as will be noted in Figure 5 of the drawings, this section or portion of string is being drawn into position to be released by pins 188 and 190 before the completed threading and tying of the previously cut section or portion of string has been effected.

It will be noted that the length of string secured to the tags 10 is dependent upon the effective length of the arm 140 about the shaft 128 which provides its axis of rotation. When it is desired to increase the length of string being secured to the tags, the bracket 166 which is adjustably secured by the bolts 254 and 256 to the table top 4 may be moved outwardly away from the axis of rotation of the arm 140 and again secured in this adjusted position by the bolts 254 and 256 which may pass through any selected openings 258 and 260 provided in the table top 4. The bracket 132 is then moved outwardly and again secured by bolts 133 in an adjusted position so that jaws 144 and 146 will deliver the string to pins 188 and 190 of the string control means 192 when the arm 140 has been adjusted. The arm 140 is then adjusted to conform with the movement of brackets 132 and 166 and secured in its adjusted position by the set screw 142 whereby the movable jaw 146 and knife 150 will be properly operated by rollers 172 and 174, respectively.

The tags 8, after having a piece of string secured thereto in the manner described, are discharged from the table top 4 by discharge means, generally referred to as 262, which comprises a carriage 264 pivoted at 263 and rocked by a cam operated shaft 265, a spring 267 being provided to normally hold the carriage in spaced relation to the table 4. At one end of the carriage is mounted a series of rollers 266 each of which is provided with a beveled gear 268 operated by a beveled gear 270 mounted upon shaft 272 which has the sprocket 32 mounted thereon and which sprocket is driven through the sprocket chain 30, as previously described. This carriage is normally held out of engagement with the tag 8 being threaded, but after the threading operation has been completed, the carriage 262 is lowered by the cam operated shaft 265 to bring the first roller 266 of the series into engagement with the tag 8.

The tag is successively engaged by the rotating rollers 266 to move the tag transversely over the table top 4 and to discharge the same in front of the machine. The movement of the carriage 264 is only slightly greater than the thickness of the thin cardboard tags and this movement can take place upon operation of the cam operated shaft 265 because of the clearance provided between the teeth of gears 268 and 270.

It is to be clearly understood that the machine is entirely automatic in its operation from the step of feeding the tags to the discharging of the tags from the machine, and that the steps of operation above described take place simultaneously and successively, as indicated, to perform the completed operation.

While I have herein described and upon the drawings shown an illustrative embodiment of the invention, it is to be understood that the invention is not limited thereto but may comprehend other constructions, arrangements of parts, details and features without departing from the spirit of the invention.

I claim:

1. In an automatic tag threading machine, the combination of means for feeding a tag into a position for threading, means for supplying a length of string to be tied to said tag, means for looping said string through an opening in said tag, means for controlling said string, said control means being associated with said looping means, said feeding and looping means being so constructed and operated that a length of string is disposed in association with said control means to be operated on by said looping means in its sequence of operation, and means for drawing the free ends of said string through said loop to secure the same to said tag.

2. In an automatic tag threading machine, the combination of means for feeding a tag into a position for threading, rotatable means for supplying a length of string to be tied to said tag, means for looping said string through an opening in said tag, means for controlling said string, said control means being associated with said looping means, said feeding and looping means being so constructed and operated that a length of string is disposed in association with said control means to be operated on by said looping means in its sequence of operation, and means for drawing the free ends of said string through said loop to secure the same to said tag.

3. In an automatic tag threading machine, the combination of means for feeding a tag into a position for threading, rotatable means for supplying a length of string to be tied to said tag, means oscillatable in a different plane than said supply means for looping said string through an opening in said tag, means for controlling said string, said control means being associated with said looping means, said feeding and looping means being so constructed and operated that a length of string is disposed in association with said control means to be operated on by said looping means in its sequence of operation, and means for drawing the free ends of said string through said loop to secure the same to said tag.

4. In an automatic tag threading machine, the combination of means for feeding a tag into a position for threading, a combined string measuring and cutting means for supplying a length of string to be tied to said tag, said means alternately gripping and releasing said string whereby a length of string is measured and the next successive length of string is gripped prior

to the operation of said cutting means to sever said first-named length of string, and means for looping said string through an opening in said tag and drawing the free ends of said string through said loop to secure the same to said tag.

5. In an automatic tag threading machine, the combination of means for feeding a tag into a position for threading, a single rotatable arm including cutting means for drawing string from a source of supply and delivering a length cut therefrom to a loop forming means, and means for looping said string through an opening in said tag and drawing the free ends of said string through said loop to secure the same to said tag.

10. 6. In an automatic tag threading machine, the combination of means for feeding a tag into a position for threading, a rotatable arm including cutting means for drawing string from a source of supply and delivering a length cut therefrom to a loop forming means, said means alternately gripping and releasing said string whereby a length of string is measured and the next successive length of string is gripped prior to the operation of said cutting means to sever said first-named length of string, means for controlling said string, and means for looping said string through an opening in said tag and drawing the free ends of said string through said loop to secure the same to said tag.

15. 7. In an automatic tag threading machine, the combination of means for successively feeding tags into a position for threading, means for supplying successively lengths of string to be tied to said tags, means for looping successively delivered lengths of string through openings in said tags, control means cooperating with said looping means for disposing a length of string to be looped by said looping means and for controlling the string to be looped through the next successively fed tag, and means for successively drawing the free ends of said lengths of string through said loops to secure the same to said tags.

20. 8. In an automatic tag threading machine, the combination of means for successively feeding tags into a position for threading, rotatable means for supplying successively lengths of string to be tied to said tags, means for looping successively delivered lengths of string through openings in said tags, control means cooperating with said looping means for disposing a length of string to be looped by said looping means and for controlling the string to be looped through the next successively fed tag, means operated by said rotatable means for operating said control means, and means for successively drawing the free ends of said lengths of string through said loops to secure the same to said tags.

25. 9. In an automatic tag threading machine, the combination of means for successively feeding tags into a position for threading, rotatable means for supplying successively lengths of string to be tied to said tags, said means comprising a rotatable arm having means for releasably holding said string and for severing desired lengths therefrom, means for looping successively delivered lengths of string through openings in said tags, control means cooperating with said looping means for disposing a length of string to be looped by said looping means and for controlling the string to be looped through the next successively fed tag, and means for successively drawing the free ends of said lengths of string through said loops to secure the same to said tags.

30. 10. In an automatic tag threading machine,

the combination of means for successively feeding tags into a position for threading, rotatable means for supplying successively lengths of string to be tied to said tags, said means comprising a rotatable arm having means for releasably holding said string and for severing desired lengths therefrom, means for controlling operation of said means for releasably holding and severing said string, means for looping successively delivered lengths of string through openings in said tags, control means cooperating with said looping means for disposing a length of string to be looped by said looping means and for controlling the string to be looped through the next successively fed tag, and means for successively drawing the free ends of said lengths of string through said loops to secure the same to said tags.

35. 11. In an automatic tag threading machine, the combination of means for successively feeding tags into a position for threading, rotatable means for supplying successively lengths of string to be tied to said tags, said means comprising a rotatable arm having means for releasably holding said string and for severing desired lengths therefrom, means for controlling operation of said means for releasably holding and severing said string, means for looping successively delivered lengths of string through openings in said tags, control means cooperating with said looping means for disposing a length of string to be looped by said looping means and for controlling the string to be looped through the next successively fed tag, means operated by said rotatable means for operating said control means, and means for successively drawing the free ends of said lengths of string through said loops to secure the same to said tags.

40. 12. In an automatic tag threading machine, the combination of means for successively feeding tags into a position for threading, rotatable means for supplying successively lengths of string to be tied to said tags, said means comprising a rotatable arm having means for releasably holding said string and for severing desired lengths therefrom, means for controlling operation of said means for releasably holding and severing said string, means for looping successively delivered lengths of string through openings in said tags, control means cooperating with said looping means for disposing a length of string to be looped by said looping means and for controlling the string to be looped through the next successively fed tag, means operated by said rotatable means for operating said control means, means for withdrawing said loops from said looping means and to spread the same, and means for successively drawing the free ends of said lengths of string through said loops to secure the same to said tags.

45. 13. In an automatic tag threading machine, the combination of a string feeding means comprising a single rotatable arm provided with fixed and movable cooperating jaws for holding said string therebetween, a movable cutting element associated with said fixed jaw, and means for moving said movable cutting element and jaw whereby a length of said string is released from between said jaws and the same severed from the string supply.

50. 14. In an automatic tag threading machine, the combination of a string feeding means comprising a single rotatable arm provided with fixed and movable cooperating jaws for holding said string therebetween, a movable knife member

mounted on said fixed jaw and cooperating with a knife edge thereof for severing said string, and means for moving said movable jaw for releasing said string from between said jaws and for grasping another portion of said string, and means for moving said knife member to sever a length of string from the string supply adjacent the portion grasped by said jaws.

15. In an automatic tag threading machine, 10 the combination of a string feeding means comprising a rotatable member provided with means for releasably holding said string, control means cooperating to operate said releasable string holding means, and means for adjusting said rotatable member and said control means for feeding various lengths of string.

16. In an automatic tag threading machine, 20 the combination of a string feeding means comprising a rotatable member provided with means for releasably holding said string, control means cooperating to operate said releasable string holding means, means for adjusting said rotatable member and said control means for feeding various lengths of string, and means for severing 25 said string at the desired length.

17. In an automatic tag threading machine, the combination of string feeding means, string 30 threading means, and control means for said string, said control means comprising means for positioning a length of string during a period of operation of said feeding means, and means for positioning said length of string for engagement by said string threading means.

18. A string control device, comprising a plurality of cooperating plate members, a plurality 35 of stops for holding a length of string in one position, and a plurality of stops for holding said string in another position when released by said first named stops.

40 19. In an automatic tag threading machine, the combination of means for successively feeding tags into a position for threading, means for supplying successively lengths of string to be tied to said tags, means for looping successively 45 delivered lengths of string through openings in said tags, control means cooperating with said looping means, said control means having stop means for holding a length of string during a period of operation of said feeding means and 50 stop means for positioning said length of string for engagement by said looping means, and means for successively drawing the free ends of said lengths of string through said loops to secure the same to said tags.

55 20. In an automatic tag threading machine, the combination of means for successively feeding tags into a position for threading, means for supplying successively lengths of string to be tied to said tags, means for looping successively 60 delivered lengths of string through openings in said tags, control means cooperating with said looping means, said control means comprising a plurality of cooperating plate members, stop means associated with said plate members for 65 holding a length of string in one position and for holding said string in another position for engagement by said looping means when released from said first-named position, and means for successively drawing the free ends of said lengths 70 of string through said loops to secure the same to said tags.

21. In an automatic tag threading machine, 75 the combination of means for successively feeding tags into a position for threading, means for supplying successively lengths of string to be

tied to said tags, means for looping successively delivered lengths of string through openings in said tags, control means cooperating with said looping means, said control means having stop means for holding a length of string during a period of operation of said feeding means and 5 stops means for positioning said length of string for engagement by said looping means, means for controlling said stop means to transfer said string from one position to the other, and means for successively drawing the free ends of said lengths of string through said loops to secure the same to said tags.

22. In an automatic tag threading machine, 10 the combination of means for successively feeding tags into a position for threading, means for supplying successively lengths of string to be tied to said tags, means for looping successively 15 delivered lengths of string through openings in said tags, control means cooperating with said looping means, said control means having stop means for holding a length of string during a period of operation of said feeding means and stop means for positioning said lengths of string for engagement by said looping means, means as- 20 sociated with said feeding means for controlling said stop means to transfer said string from one position to the other, and means for successively drawing the free ends of said lengths of string through said loops to secure the same to said tags.

23. In an automatic tag threading machine, the combination of means for successively feeding tags into a position for threading, means for supplying successively lengths of string to be 30 tied to said tags, means for looping successively delivered lengths of string through openings in said tags, control means cooperating with said looping means, said control means comprising a plurality of cooperating plate members, stop 35 means associated with said plate members for holding a length of string in one position and for holding said string in another position for engagement by said looping means when released from said first-named position, means for controlling said stop means to transfer said string from one position to the other, and means for successively drawing the free ends of said lengths of string through said loops to secure the same to said tags.

40 24. In an automatic tag threading machine, the combination of means for successively feeding tags into a position for threading, means for supplying successively lengths of string to be tied to said tags, means for looping successively 45 delivered lengths of string through openings in said tags, control means cooperating with said looping means, said control means comprising a plurality of cooperating plate members, stop 50 means associated with said plate members for holding a length of string in one position and for holding said string in another position for engagement by said looping means when released from said first-named position, means associated with said feeding means for controlling said stop 55 means to transfer said string from one position to the other, and means for successively drawing the free ends of said lengths of string through said loops to secure the same to said tags.

60 25. In an automatic tag threading machine, 70 the combination of means for successively feeding tags into a position for threading, means for supplying successively lengths of string to be tied to said tags, means for looping successively 65 delivered lengths of string through openings in 75

said tags, control means associated with said looping means, said control means having means for receiving drawn string from said supply and means for simultaneously positioning severed lengths of string for said looping means, and means for successively drawing the free ends of said lengths of string through said loops to secure the same to said tags.

26. In an automatic tag threading machine, 10 the combination of a string feeding means comprising a rotatable member provided with means for releasably holding said string, means for adjusting said rotatable member for feeding varying lengths of string, and control means cooperating with said releasable string holding means for operation thereof.

27. In an automatic tag threading machine, the combination of a string feeding means, said means comprising a rotatable member provided 20 with means for releasably holding said string and means for severing said string at the desired length, means for adjusting said rotatable member for feeding varying lengths of string, and control means cooperating with said releasable string holding means and severing means for operation thereof.

28. In an automatic tag threading machine, the combination of means for successively feeding tags into a position for threading, means for supplying successively lengths of string to be tied to said tags, means for looping successively delivered lengths of string through openings in said tags, control means associated with said looping means, said control means having means for receiving drawn string from said supply and means for simultaneously positioning severed lengths of string for said looping means, said string supplying means having means cooperating with said control means for operating the same, and means 35 for successively drawing the free ends of said lengths of string through said loops to secure the same to said tags.

29. In an automatic tag threading machine, the combination of means for successively feeding 40 tags into a position for threading, a rotatable head having a radially extending arm provided with means for supplying successively lengths of string to be tied to said tags, means for looping successively delivered lengths of string through 45 openings in said tags, control means associated with said looping means, said control means having means for receiving drawn string from said supply and means for simultaneously positioning severed lengths of string for said looping

means, and means for successively drawing the free ends of said lengths of string through said loops to secure the same to said tags.

30. In an automatic tag threading machine, the combination of string feeding means, string 5 threading means, and control means for said string, said control means having means for positioning a length of string for engagement by said string threading means, said control means being further provided with positioning means for another length of string fed by said feeding means while said first length of string is moved by said threading means.

31. In an automatic tag threading machine, the combination of string feeding means, string 15 threading means, control means for said string, said control means having means for positioning a length of string for engagement by said string threading means, said control means being further provided with positioning means for another 20 length of string fed by said feeding means while said first length of string is moved by said threading means, and means for transferring said last-named length of string from said second-named 25 positioning means to said first-named positioning means.

32. In an automatic tag threading machine, the combination of string feeding means, string 30 threading means, control means for said string, said control means having means for positioning a length of string for engagement by said string threading means, said control means being further provided with positioning means for another length of string fed by said feeding means while said first length of string is moved by said threading means, and means for operating said control 35 means for transferring said last-named length of string from said second-named positioning means to said first-named positioning means.

33. In an automatic tag threading machine, the combination of string feeding means, string 40 threading means, control means for said string, said control means having means for positioning a length of string for engagement by said string threading means, said control means being further provided with positioning means for another length of string fed by said feeding means while said first length of string is moved by said threading means, and means on said feeding means for 45 operating said control means for transferring said last-named length of string from said second-named positioning means to said first-named positioning means.

ROY G. TRAVIS.
